[57] CLAIM

The ornamental design for a toucan shaped handle, as shown and described.

DESCRIPTION

FIG. 1 is a top front perspective view of a toucan shaped handle showing our new design;

FIG. 2 is a front elevational view thereof;

FIG. 3 is a right side elevational view thereof;

FIG. 4 is a left side elevational view thereof;

FIG. 5 is a top plan view thereof;

FIG. 6 is a bottom plan view thereof; and,

FIG. 7 is a rear elevational view thereof.

The broken line showing of a spoon bowl in FIGS. 1-7 is environmental only and forms no part of the claim design.
